ART OF COILING HOT METAL STOCK

Application filed February 23, 1929. Serial No. 342,223.

The present invention relates in general to the coiling of hot metal stock, such as rods, bars or the like, as delivered at high speed from the finishing passes of a rolling mill. In particular, the invention is concerned with the coiling, on a high speed automatic reel of the so-called "pouring" type, of stock whose finished section is other than round,— an operation that heretofore has presented almost insuperable difficulties, because it has been impossible, in the presentation gravitationally of such stock to such a reel, to establish for the stock section, approaching the reel at an indeterminate and unstable inclination, the necessary constant relation to the vertical or substantially vertical axis of the reel.

In the case, for example, of stock of oblong or flat rectangular section, emerging flatwise from the finishing passes of the mill, the section must acquire a ninety degree twist, so that such relatively flat stock will pass by combined downward gravitational and forward movement onto the "pouring" reel in correct coiling position, i. e., with the major axis of the oblong section in parallelism, or nearly so, with the substantially vertical axis of rotation of the reel. But a twist once imparted to such stock continues indefinitely and its effect on such stock is cumulative; the advancing first end of the stock acquires more and more twist as its distance from the twisting instrumentality increases.

According to this invention, the stock is caused to pass downwardly and forwardly into the "pouring" reel, with its section turned or twisted into the desired relation to the reel axis, by imparting to said stock, at or near its point of delivery from the finishing rolls, a twist of lesser angular magnitude than that ultimately required; provision is made, in the absence of any undue restraining or frictional influences on the moving stock, for keeping this twist from getting out of control and for positively stopping or counteracting the twisting tendency so set up, when and as the twist attains the desired angular magnitude, in order to eliminate any resultant twisting action in the stock after it gets on the reel. The manner in which

the above and other objects and advantages of the invention may be attained is fully set forth in the following detailed description of said invention, taken in connection with the accompanying illustrative drawings, in which—

Fig. 1 is a diagrammatic plan view showing an arrangement of coiling apparatus adapted to the carrying out of our invention.

Fig. 2 is a view in side elevation, and partly in section, on a larger scale, showing the mode of operation of the twist-imparting and twist-controlling devices.

Fig. 3 is a section of the flattened stock, as it appears in the plane of the line 3—3 of Fig. 2.

Fig. 4 is a section on the line 4—4 of Fig. 2.

Fig. 5 is a section much enlarged on the line 5—5 of Fig. 1.

Fig. 6 is the section represented by the two lines 6—6 of Fig. 2.

Like reference characters refer to like parts in the different figures.

Referring first to Fig. 1, the finishing rolls of a rolling mill, as indicated at 1, may be conventionally arranged for the delivery of the finished stock 2 to either or both of a pair of parallel pipes 3, 3, each of the latter alining with a suitable switching pipe 4, adapted to direct the stock, alternately or selectively as desired, to two or more reel-delivery pipes 5, 5. Each of these pipes 5, 5 provides a curved path which the stock takes to a constantly revolving reel 6 of the so-called automatic or continuous "pouring" type, whereon a plurality of fingers 7, 7 provide the means by which the first end of the stock, as delivered into the reel, is caught and held, in the act of forming a coil on said reel within its inclosure 8. As best shown in Fig. 2, the path of the stock, as provided by each reel-delivery pipe 5, takes the usual and necessary downward inclination toward the reel, and said path also preferably, as shown in Fig. 1, has a distinct lateral curvature, for reasons which will hereinafter appear.

Assuming the finished stock to be of oblong or rectangular section and to emerge from the finishing rolls 1, 1 in the flatwise position indicated at a, Fig. 3, it is evident that said

stock, in order to be coiled on a reel 6, must be delivered to said reel on edge, rather than flatwise, i. e., with its section upright, or twisted through ninety degrees from the 5 position illustrated at *a*. To secure this result, or a similar result in the case of various other sections whose reeling presents similar problems, we propose, as shown in the drawings, to impart to the stock, at or 10 near its point of delivery from the finishing rolls 1, 1, a twist of considerably less magnitude than that ultimately required,—which latter, in the example herein considered, is, as stated ninety degrees. This twist in the 15 stock, as delivered from the finishing rolls 1, 1 may be imparted in any suitable way, by the use of any known type of twist delivery guide or its equivalent, but we prefer to effect the same by passing the stock between 20 a set of rollers 9, 9, here shown as three in number, arranged in staggered relation, with their axes at a relatively low angle to the horizontal, so that the stock, in passing between said rollers, has its section slightly 25 twisted, as shown at *b*, Fig. 4, from the flatwise position indicated at *a* in Fig. 3.

The angular magnitude of this twist is dependent, to a considerable extent, upon the distance that the stock can run out before 30 coming under the influence of the twist-arresting instrumentalities, which, as herein-after described, preferably take the form of a set of rollers 10, 10, of the same number and the same staggered arrangement as the rollers 35 9, 9, but having their axes, in this instance, where a ninety degree twist is to be obtained, perpendicular, so as to receive and hold the stock section in the upright position shown at *d* in Fig. 6. That is to say, the twist-im- 40 parting rollers 9, 9 need ordinarily to have an axial inclination of only about ten degrees, for the ultimate production at the rollers 10, 10 of a ninety degree twist, if the distance between said sets of rollers 9, 9 and 10, 10 is, 45 say, approximately ninety per cent of the total distance between the two holding points, i. e., the rolls 1, 1 and the rollers 10, 10. No hard and fast rule for determining the exact angular setting of the rollers 50 9, 9 in any given case can be formulated, because there are so many variable factors that affect the twist that rapidly moving stock may acquire,—for example, the inherent twisting tendency that such stock may have 55 by reason of the finishing rolls being slightly crossed, or by reason of a variety of other causes.

The twisting rollers 9, 9 are preferably located, as shown, in relatively close proximity to, say four to six feet from, the finishing rolls 1, 1 of the mill, so that the latter may serve more effectively as the holding point from which the twist is started. As shown in Fig. 1, each set of twisting rollers 65 9, 9 may be arranged between the pipe sec-

tion 3 and the switching pipe 4, but obviously our invention is not limited in this respect, as said twisting rollers could as well be located in either of these pipes, or, if desired, in the entrances to the several reel-delivery 70 pipes 5, 5. As previously stated, the twist of relatively small magnitude imparted by the rollers 9, 9 attains a progressively greater magnitude as the stock runs out further and further in the reel delivery pipe 5, as shown 75 for example in Fig. 5. The fact that each pipe 5 must incline downwardly toward the reel 6, as previously noted, makes it preferable to define with said pipe a path that curves laterally, as shown in Figs. 1 and 5, 80 from a straight-line runout in the direction of delivery from the rolls 1, 1. By so curving the path in the horizontal plane, the desired downward curvature in the vertical plane can be obtained, without having to bend the stock 85 on edge. Such a bending on edge, to obtain the desired downgrade movement toward the reel 6, would be required, if the stock were not allowed to deflect laterally beyond the rollers 9, 9,—unless the downward inclination 90 is established between the finishing rolls 1, 1 and the twisting rollers 9, 9, a condition, however, that would increase the distance between those points. In the arrangement here shown, with the pipe 5 curved in both the 95 horizontal and vertical plane, the short axis of the section, as shown in Fig. 5, comes approximately in the plane of bend of said pipe, and thus there is no undue resistance 100 to the downward or the lateral bending.

In its movement between the twist-imparting rollers 9, 9 and the twist-arresting rollers 10, 10, the stock, as shown in Fig. 5, gradually becomes more and more upright, until full upright position is reached as it enters between the rollers 10, 10. In connection with said rollers 10, 10, as well as the preceding rollers 9, 9 and the succeeding rollers 11, 11, the staggered arrangement, as will be noted, lends itself to a relatively easy entrance of 110 the stock, notwithstanding that the latter's first end may be out of alinement or registry, either laterally or angularly, or both, with the passage that is provided between the several staggered rollers of each set. For example, a glancing impact of the stock on the first-encountered roller of such a set is found to be no hindrance to passing by the second roller, and the same condition holds true 115 between the second and third rollers, whereas with guides of different character, such impact might well result in disastrous buckling of the rapidly moving stock. These roller guides prevent scratching of the stock, and moreover, the provision of three staggered 120 rollers, rather than two rollers in directly opposed relation, allows the stock to vary slightly in thickness, without need for making corresponding adjustments of said rollers.

As previously noted, the office of the set of staggered rollers 10, 10 is to establish a hold on the stock as presented to said rollers, in the present instance, in a condition that

5 represents a twist of ninety degrees from its flatwise delivery by the finishing rolls 1, 1. With the stock so held, its subsequent and almost immediate passage through the similarly arranged set of rollers 11, 11 procures 10 the removal, entirely, of the twisting tendency originally set up by the rollers 9, 9.

In other words, in substantially the same manner as the finishing rolls 1, 1 cooperate, as a holding point with the staggered twisting 15 rollers 9, 9 to inaugurate the twist, so the vertical rollers 10, 10, as a holding point, render the other vertical rollers 11, 11 effective to remove all traces of said twist,—whereby the stock, by reason of its immediately-following edgewise presentation to the reel 6, will have no tendency whatsoever 20 to twist during the process of its being coiled up on said wheel.

We claim,

25 1. In apparatus of the class described, a "pouring" reel for the continuous reception and coiling of metal stock whose section other than round would normally approach said reel at an indeterminate and unstable inclination, and means operable on said stock on its way to said reel for establishing and maintaining at the entrance to said reel a predetermined relation between the reel axis and a particular axis of the stock section, 30 thereby to secure its passage onto said reel in a sectional position permissive of the coiling operation.

2. The combination, with a "pouring" reel for the continuous reception and coiling of 40 hot metal stock, as delivered from the mill with its section in a position other than that adapted for coiling, of means operable on said stock on its way to said reel for establishing and maintaining at the entrance to said reel 45 a position of the stock section that is permissive of the coiling operation.

3. The combination, with a "pouring" reel for the gravitational reception and continuous coiling of hot metal stock, whose section 50 as delivered from the mill, is in a position other than that adapted for coiling, of means for starting a twist in said stock, outwardly from its delivery point, such as to dispose said section in a position permissive of coiling before it reaches the reel, and means for thereupon stopping said twist and holding said stock section in said last named position, as it passes onto said reel.

4. The combination, with a "pouring" reel 60 for the gravitational reception and continuous coiling of hot metal stock, of means for starting a twist in said stock, outwardly of its delivery point, such as to establish a predetermined relation between the reel axis 65 and a particular axis of the stock section be-

fore reaching the reel, and means for thereupon arresting said twist and holding the stock in said predetermined relation as it passes to the reel.

5. In apparatus of the class described, the combination with an automatic "pouring" reel for the gravitation reception and coiling of continuously delivered stock, of means 70 acting on said stock adjacent its delivery point to establish in advance of reeling, a predetermined relation between the reel axis and a particular axis of the stock section, and means acting thereafter on the stock to maintain said predetermined relation as the stock passes into said reel.

6. Apparatus of the class described, for the reeling of continuously delivered hot metal stock whose section is other than round, comprising a "pouring" reel, means interposed between the delivery point of said stock and the reel, for first imparting a twist to said stock, and then arresting said twist, when a predetermined relation between the reel axis and a given axis of the stock section has been established by said twist.

7. Apparatus of the class described, for the reeling of continuously delivered hot metal stock whose section is other than round, comprising a "pouring" reel, a twist guide adjacent the delivery point of said stock, and means for arresting the twist imparted by said guide when it has established a particular axis of the stock section in a predetermined relation to the axis of the reel.

8. Apparatus of the class described, for the reeling of continuously delivered hot metal stock whose section is other than round, comprising a "pouring" reel, a twist guide adjacent the delivery point of said stock, means for arresting the twist imparted by 100 said guide when it has established a particular axis of the stock section in a predetermined relation to the axis of the reel, and means for holding said stock against further twisting as it passes into said reel.

9. Apparatus of the class described, for the reeling of continuously delivered hot metal stock whose section is other than round, comprising a "pouring" reel, a twist guide adjacent the delivery point of said stock, means 115 for arresting the twist imparted by said guide when it has established the major axis of the stock section in a predetermined relation to the substantially vertical axis of the reel, and means for thereafter removing the 120 twisting tendency of said stock, prior to its passage into the reel.

10. Apparatus of the class described, for the reeling of continuously delivered hot metal stock whose section is other than round, comprising a "pouring" reel, means for imparting a twist to said stock, such as to establish at a predetermined point, a position 125 of the stock section relative to the sub- 130

stantially vertical reel axis that permits the stock to be coiled, means acting on said stock at said predetermined point to hold it in said position, and means beyond said point for removing the twisting tendency of said stock, whereby it passes onto the reel in the desired coiling position.

11. In the art of coiling hot metal stock, continuously delivered from the finishing rolls with its section in a position other than that adapted for coiling, the improvement which consists in first imparting to said stock, near its delivery point, a twist of sufficient magnitude to establish a "pouring" position of the section at a point in advance of a "pouring" reel, and then removing, beyond said point, the twisting tendency previously imparted.

12. In the art of coiling hot metal stock, continuously delivered from the finishing rolls with its section in a position other than that adapted for coiling, the improvement which consists in first imparting a predetermined twist to such stock, such as to turn the section into coiling position at a point in advance of the coiling reel, and between said point and said reel procuring the complete removal of the twist previously imparted to said stock.

13. In the art of coiling continuously delivered hot metal stock, whose section at the finishing rolls emerges flatwise, the improvement which consists in first imparting a twist to said stock near its point of delivery, whereby at a predetermined distance from said delivery point the stock section will stand edge-wise, in a position permissive of coiling, and from there on to a "pouring" reel, procuring the removal of the twist previously imparted to said stock.

14. In the art of coiling continuously delivered hot metal stock whose section at the finishing rolls is in a position other than that adapted for coiling, the improvement which consists in first twisting said stock so that, at a predetermined point beyond said twisting point, its section will turn into a position permissive of coiling, then applying to said stock a restraining force to hold said section in said coiling position, and finally, between said restraining point and a "pouring" reel, removing all traces of twist from said stock.

15. In the art of coiling hot metal stock continuously delivered from finishing rolls with its section in a position other than that adapted for coiling, the improvement which consists in first passing said stock through a twist guide, whereby at a predetermined point beyond said guide, the stock section will be turned into coiling position, and then passing said stock through a succession of straightening guides to remove the twist and to hold the stock with its section in coiling position.

16. In apparatus of the class described,

for the continuous coiling of hot metal stock whose section is other than round, a twisting means operative on the stock near its delivery point and consisting of a plurality of rollers arranged in staggered relation, for the passage of the stock therebetween.

17. In apparatus of the class described, for the continuous coiling of hot metal stock whose section is other than round, a set of staggered rollers adapted to impart a twist to the stock near its delivery point, and a plurality of sets of similar rollers, with their axes at an angle to those of the first set, for removing the twist, prior to passage of the stock onto the reel.

18. In the art of coiling continuously delivered hot metal stock of a section other than round, the improvement which consists in starting a twist in said stock such as to establish at a predetermined point in its movement toward the reel, the desired substantial parallelism of the stock section's major axis to the substantially vertical reel axis, and then holding the stock in the said substantially parallel relation and removing the twist therefrom.

19. In the art of coiling continuously delivered hot metal stock of a section other than round, the improvement which consists in starting a twist in said stock such as to establish at a predetermined point in its movement toward the "pouring" reel the substantial parallelism of the stock section's major axis to the vertical axis of said reel, directing the stock, beyond said twisting point in a path that slopes downwardly toward said reel, and beyond said predetermined point holding the stock in the said substantially parallel relation and removing the twist therefrom.

20. In the art of coiling continuously delivered hot metal stock of a section other than round, the improvement which consists in starting a twist in said stock such as to establish at a predetermined point in its movement toward the reel the substantial parallelism of the stock section's major axis to the substantially vertical reel axis, directing the stock, beyond said twisting point, in a path that slopes downwardly toward said reel with a lateral deflection to avoid bending of the stock on edge, and beyond said predetermined point holding the stock in the position aforesaid and removing the twist therefrom.

21. The herein described method of coiling, on an automatic "pouring" reel, continuously delivered hot metal stock whose section is other than round, which consists in passing said stock, just beyond its point of delivery, between a set of staggered rollers so arranged as to establish at a predetermined point in the stock's movement toward the reel substantial parallelism of the major axis of the stock section to the reel axis, causing said stock on its way to said predetermined point to deflect laterally and downwardly from the line

of its delivery from the finishing rolls of the mill, passing said stock at said predetermined point between a second set of staggered rollers whose contact with the section holds it in the aforesaid parallel relation, and thereafter passing said stock between a third set of staggered rollers, arranged to hold said section in said parallel relation as the stock passes onto the reel.

10 22. The method of presenting edgewise to an automatic "pouring" reel, strip material whose delivery is flatwise, which consists in initiating in the flatwise-delivered material a twist of such magnitude and at such a distance from the reel as will produce the desired edgewise position of the strip before it reaches the reel, and from there on holding the strip against twisting.

20 23. In apparatus of the class described, the combination with an automatic "pouring" reel, of means for presenting thereto, in a substantially edgewise or coiling position, strip material whose position at its delivery point is substantially flatwise, and means for restraining said strip's attainment of edgewise position until it reaches the entrance to said reel.

25 24. In apparatus of the class described, the combination with an automatic "pouring" reel, of means for presenting thereto, in a substantially edgewise or coiling position, strip material whose position at its delivery point is substantially flatwise, said means comprising twist-imparting devices so spaced from the reel as to produce in said material only as it substantially reaches the entrance to said reel, the magnitude of twist that establishes its edgewise position.

30 25. In apparatus of the class described, the combination with an automatic "pouring" reel, of means for presenting thereto, in a substantially edgewise or coiling position, strip material whose position at its delivery point is substantially flatwise, said means comprising twist-imparting devices so spaced from the reel as to produce in said material only as it substantially reaches the entrance to said reel, the magnitude of twist that establishes its edgewise position, and means at 35 said reel entrance for removing the twisting tendency produced by said twist-imparting devices.
